PROCESS FOR MAKING ACETYLENE USING A
PLASMA ARC FURNACEJohn White Colton, Pelham Manor, N.Y., assignor to
Halcon International, Inc., a corporation of DelawareFiled Oct. 24, 1962, Ser. No. 234,898
10 Claims. (Cl. 260—679)

This invention relates to the plasma technique in high temperature chemical reaction, more particularly to processes and apparatus for producing acetylene and the like materials from a plasma gas which contains at least minor amounts of hydrocarbons which tend to form pulverulent carbon and form a deposit thereof on the anode which can easily choke the anode passage, and especially to such processes wherein the plasma gas is hydrogen containing 5 to 10% of methane and the anode is subjected to vibration at a frequency in the audible range and at an amplitude in the range of from 1 to 20% of the diameter of the anode passage, whereby deposit of carbon is removed or prevented.

Plasma technology has achieved a measure of commercialization, and in such processes for preparing acetylene from methane, the plasma gas is hydrogen contaminated with minor amounts of lower hydrocarbons, e.g., from 5 to 10% of methane. These hydrocarbons tend to crack and deposit carbon under the plasma arc environment. This deposit chokes the anode passage and requires shut-down. The art is confronted by the problem of providing even more efficient plasma processes which avoid such drawbacks and permit continuous efficient operation.

The discoveries associated with the invention and relating to the solution of the above problems, and the objects achieved in accordance with the invention as set forth herein include the provision of: a process for conducting a high temperature reaction by means of a plasma wherein a gas containing carbonaceous material is subjected to an electrical arc to form a plasma and simultaneously tends to deposit pulverulent carbon which tends to block the arc outlet, including the improvement which comprises subjecting the arc zone to vibration at a frequency within the audible range and at an amplitude of 1 to 20% of the average diameter of the arc zone outlet, whereby objectionable deposition of carbon is avoided; such a process wherein the plasma gas is hydrogen containing from 5 to 10% of a lower hydrocarbon, such as methane, ethane, or the like; such a process wherein the hydrocarbon is principally methane; such a process wherein the hydrogen contains about 10% of methane; such a process wherein there is an about 80% conversion of methane to acetylene per pass; such a process using an energy consumption of about 55,000 kilowatt per hour, a hydrogen feed rate of about 975 pound mols per hour and a methane feed range of about 1200 mols per hour; such a process using a plurality of arc outlet zones each of about 1.5 inches average diameter; such a process using a vibration of an amplitude of about 0.15 inch and of a frequency in the range of 20 to 1000 cycles per second; such a process wherein the frequency is about 100 cycles per second; an apparatus adapted for carrying out high temperature reactions using a plasma including arc means provided with a cathode and an anode as well as a plasma gas inlet and a plasma outlet, said means being provided with vibrating means for subjecting at least said anode to vibration in its axial direction in a frequency in the audible range and of an amplitude of 1 to 20% of the average diameter of the arc outlet, and a reaction chamber flexibly connected with the plasma outlet, said chamber being provided with reactant inlet means and reaction mixture outlet means; and other objects which

2

will be apparent as details or embodiments of the invention are set forth hereinafter.

The accompanying drawing is a schematic vertical sectional diagram of a preferred embodiment of the invention.

EXAMPLE 1

Referring to the accompanying drawing, acetylene is produced by passing a plasma gas such as hydrogen containing methane into the plasma arc, and the plasma formed is mixed with reactant gas (methane) and the high temperature reaction takes place directly after this mixing. The mixture is then rapidly cooled by coolant (water) and the resulting mixture is passed to usual recovery means. The by-product hydrogen is used as plasma gas.

Operation with an energy consumption of 55,000 kilowatt per hour using a hydrogen feed of about 975 lb. mols per hour containing 10% (mol) methane and a (95%) methane reactant gas feed of 1200 lb. mols per hour, there is obtained about 80% of acetylene based on the methane reacted. There is a deposit of powdered carbon on the anode and this tends to block the anode passage way, necessitating shutdown after an about one hour period of operation.

By vibrating the arc assembly using 10 anode nozzles (each of 1.5 inches diameter) and subjecting each to an axial vibration in the audible range e.g. 100 cycles/second, at an amplitude of about 0.15 in. (10% of the diameter of the anode passage), similar yields are obtained, but there is no objectionable deposit of carbon so that the process may be operated over long periods without shutdown due to clogging.

As to the apparatus, in the arc section, 1 is a casing made of insulating material, as for example synthetic resin, such as polyethylene, nylon, or the like. This casing surrounds a body 2 of electrically conductive metal as, for example, copper, copper alloy, brass, aluminum, steel, or the like. Body 2 has a central female threaded bore 40 into which the electrode holder 3 of conductive metal is screwed. The electrode holder 3 has an end adjusting cap 4 of suitable electrical insulating materials as, for example, synthetic resin or like. The body 2 also has the annular groove 5 in communication with the bores or conduits 6 and the threaded connection 7, into which the water-cooled current conductor or cable 8 is screwed. Screwed on to the conductive body 2 is the body 9 of insulating material as, for example, synthetic resin, such as polyethylene, nylon, or the like. The bodies 2 and 9 are sealed to each other by means of the gasket seal 10. The insulating body 9 has a central bore 12 of larger diameter than the electrode holder 3, which surrounds the electrode holder and is flared outwardly at its upper end in flow communication with the bores 6. The electrode holder 3 has at its lower end a central bore or passage 13 in communication with the thin hollow tube 14. The bore 12 is also in communication with the passage 13 by means of the side bore 15. The lower end of the insulating body 9 is provided with the bore 16 in communication with the bore 12, and with a tube or pipe 17 provided as an extension of the bore 16.

The lower end of the insulating body 9 is also provided with the bore 18 having the pipe 19 provided as an extension thereof. The bore 18 leads to an annular recess 20 in the insulating body 9. The bore 13 in the electrode holder 3 is widened at 22 around the tube 14 and provided with a passage way 23-24 leading to the bore 18 and recess 20. A metallic pipe 25, preferably of copper, copper alloy, steel, or the like, is fitted around the insulating body 9 in the form of a casing and sealed thereto by means of the O-ring seals 26. The casing 25 is provided with the

threaded nipple 27 for connection to a water-cooled electrical cable. The nipple 27 leads into the recess 20.

Screwed into the lower end of the electrode holder 3 is permanent electrode 28 constructed, for example, of tungsten or thoriated tungsten. The electrode 28 is hollow and its hollow interior is larger than the tube 14, so that the tube 14 extends down into the interior thereof, leaving annular space between the inner wall of the electrode 28 and the outer surface of tube 14. A nozzle body 29, preferably of the same metal as the casing 25, is secured to the casing by means of the flange 30. A disc 31, of a refractory material, such as aluminum oxide, is positioned between the nozzle body 29 and the insulating body 9. The disc 31 has openings for the pipes 17 and 19 and is provided with a central bore. The nozzle body 29 has the nozzle 32 fitted therein. This nozzle, 32, of platinum, silver or preferably of copper, is soldered in fluid-type contact with the nozzle body, leaving the annular space 33 therebetween. The annular space 33 is connected on one side with the pipe 17 by means of the bore 34 and on the other side with the pipe 19 by means of the bore 35. The nozzle body and the refractory disc 31 define the enclosed chamber 36, into which the electrode 28 extends.

The insulating body 9 is provided with the female threaded connection 37 leading into the gas passage 38, which leads to annular gas distributing grooves 39, which in turn leads into the annular gas outlet space 40 surrounding the electrode 28.

In place of the annular gap formed by the gas distributing grooves leading into the space 40, a single enclosed groove may be provided into which the passage 38 leads. This groove may be connected to the space 40 by a multiple number of annularly positioned holes. These holes should preferably be positioned at an angle from the center of the axis of the electrode 28 so as to provide a controlled amount of swirl to the gas. The holes may thus be positioned at an angle of 10-30° from the axis of the nozzle 28. In all cases it is extremely important that an even gas distribution around the electrode be provided.

The end of the electrode 28 has a frusto-conical shape, i.e., a conical shape, the tip of which is flattened and extends partially into the nozzle 32, which is cylindrical in shape.

In operation water-cooled electrical cables are connected at 7 and 27. These cables are of conventional construction and consist of a metallic electrical conductor surrounded by an insulation covering provided with cooling water passages through which cooling water is forced. The cooling water from the water-cooled electrical cables 8 flows into the annular groove 5, through bores 6 and through the annular passage formed by bore 12. From the annular passage formed by bore 12 a part of the cooling water flows through the bore 15, bore 13 and tube 14 to the interior of the hollow electrode 28, cooling the same, and up through annular space around tube 14, out through the passages 23-24 into the bore 18, to the annular recess 20 and out through the water cooled electrical cable connected at 27 to a suitable drain, or for recirculation. Another portion of the cooling water from the annular passage formed by bore 12 flows through the bore 16, pipe 17, bore 34, around the annular space 33, cooling nozzle 32 through the bore 35, pipe 19, bore 18, to the annular recess 20 and out through the water-cooled electrical cable with the other portion of the water.

A source of electrical current as, for example, from a conventional welding generator, is connected to the water-cooled cable 8. This current flows through the conductive body 2 to the electrode holder 3 and then up to the electrode 28. The lead of opposite polarity or ground is connected at 27 and is in electrical communication with the nozzle 32 by means of the nozzle body 29 and casing 25.

With cooling water flowing through the water-cooled leads and the device in the manner previously described,

and with a suitable source of current connected at 7 and 27, an arc may be struck between the nozzle 32 and electrode 28, either by screwing the electrode body 3 by means of the insulating cap 4 downwardly to initially strike the arc and by retracting the same by screwing in the reverse direction, or by providing an initial high-frequency source of alternating current connected at 7 and 27. After the arc is struck the same may be suitably adjusted by screwing the electrode holder 3.

10 Prior to striking the arc the hydrogen plasma forming fluid at a suitable pressure is passed in at 37, passes through the passages 38-39 to the outlet 40 into the chamber 36. The plasma forming gas will flow along the electrode 28 over the frusto-conical tip of the electrode and through the nozzle. The plasma forming gas will form a sheath around the arc between it and the inner surface of the nozzle 32, constricting the arc and forcing the same through the nozzle, as is indicated at 41. The plasma forming gas will be converted in the nozzle to a free plasma and will leave the nozzle and pass out of contact with the arc as a free plasma stream, being projected from the nozzle. The plasma forming gas is passed into the chamber 36, preferably at a velocity and/or pressure sufficient so that the same will emerge from the nozzle 32 as a free plasma stream having a velocity of at least 5, and preferably of at least 50 feet per second, and most preferably of at least 500-1000 feet per second.

15 The axial vibrating means is made up of member 55 attached to the arc means via weld 55a. It is attached to drive shaft 57 via pin 56. The drive shaft is supported in bearings 58 and 59. The drive shaft is connected with link 61 via pin 60, and the link 61 is attached via pin 63 to an eccentric drive 62, which may be powered by any convenient means such as an electric motor (not shown). The bearings may be supported in known manner. If desired, the arc means may be supported by flexible means e.g. (wire and spring support from overhead), or in any convenient manner.

20 The reactor means 100 is made up of a casing 49, to which is attached expansion joint 46 by means of weld 48. The expansion joint is connected via link and bolt connection means 44 and 45 to plate member 42 which is fixedly attached to the arc by screw means 43. There is a clearance between casing 49 and the plate 42, to allow for vibration or relative movement of the plate relative to the casing 49. The casing is provided with a cooling channel through which water is passed in via connection 51 and out via connection 52. It is also provided with reactant gas feed means 50 and quench water feed means 53 as well as reaction mixture outlet means 54 which leads to usual recovery means.

25 In operating the vibrator, the eccentric drive is operated at a speed of rotation to give the desired rate of vibration. Instead of an eccentric drive, any other convenient vibration means may be used. Additional vibrations may be supplied in directions other than axial, if desired. Also, any convenient arc means may be used. Generally, the advantages of the invention are particularly apparent 30 when the plasma forming hydrogen contains 5 to 10% of methane; however, the invention is operative with higher or lower amounts. Generally, the vibration is at frequency in the audible range, and may be from 20 to 1000 cycles per second. From the economic viewpoint, the lowest frequency which permits extended operation is to be preferred. The amplitude of vibration is in the range of about 1 to 20% of the average diameter of the anode passage, which passage may be of a diameter in the range of about 0.5 to 3.0 inches.

35 Any convenient power consumption may be used as well as any convenient hydrogen feed rate and methane feed rate, provided the conditions selected give a reaction temperature or condition such that the desired conversion of methane to acetylene is obtained.

It is indeed surprising that one may achieve long continued operation in accordance with the invention, especially in view of the marked economies resulting therefrom since it substantially minimizes or eliminates the need for high purification of the by-product hydrogen separated in the recovery system and recycled.

In view of the foregoing disclosures, variations and modifications thereof will be apparent to one skilled in the art, and it is intended to include within the invention all such variations and modifications except as do not come within the scope of the appended claims.

What is claimed is:

1. In a process for preparing acetylene from a plasma containing lower hydrocarbons which tend to deposit pulverulent carbon which tends to block the arc outlet, the improvement which comprises subjecting the entire arc zone to vibration as a unit in the direction of the axis of the arc at a frequency within the audible range and at an amplitude of 1 to 20% of the average diameter of the arc zone outlet, whereby objectionable deposition of carbon is avoided.

2. A process of claim 1 wherein the plasma gas is hydrogen containing from 5 to 10% of a lower hydrocarbon.

3. A process of claim 2 wherein the hydrocarbon is principally methane.

4. A process of claim 3 wherein the hydrogen contains about 10% of methane.

5. A process of claim 4 wherein there is an about 80% conversion of methane to acetylene per pass.

6. A process of claim 5 using an energy consumption of about 55,000 kilowatts per hour, a hydrogen feed rate

of about 975 pound mols per hour and a methane feed range of about 1200 mols per hour.

7. A process of claim 6 using a plurality of arc outlet zones each of about 1.5 inches average diameter.

8. A process of claim 7 using a vibration of an amplitude of about 0.15 inch and of a frequency in the range of 20 to 1000 cycles per second.

9. A process of claim 8 wherein the frequency is about 100 cycles per second.

10. An apparatus adapted for carrying out high temperature reactions using a plasma including arc means provided with a cathode and an anode as well as a plasma gas inlet and a plasma outlet, said means being provided with vibrating means for subjecting said cathode and anode to vibration as a unit in the direction of the axis of said cathode and anode at a frequency in the audible range and at an amplitude of 1 to 20% of the average diameter of the arc outlet, and a reaction chamber flexibly connected with the plasma outlet, said chamber being provided with reactant inlet means and reaction mixture outlet means.
